COMBINED DISPLAY CARTON AND CARRIER FOR BOTTLES

Noel G. Fischer, Richardson, Tex., assignor to Liquid
Paper Corporation, Dallas, Tex.

Filed Dec. 3, 1973, Ser. No. 421,057

Term of patent 14 years

Int. Cl. D9—03

U.S. Cl. D9—179

Figure 1

Figure 2

Figure 3

Figure 4

FIG. 1 is a perspective view of a combined display carton and carrier for bottles showing my new design;

FIG. 2 is a top plan view on a reduced scale;

FIG. 3 is a side elevational view thereof; and

FIG. 4 is an end elevational view thereof.

I claim:

The ornamental design for a combined display carton and carrier for bottles, substantially as shown and described.
